[57] CLAIM

The ornamental design for a handle for flatware, as shown and described.

DESCRIPTION

FIG. 1 is a top perspective view of a handle for flatware showing my new design;
FIG. 2 is a right side elevational view, the left side elevational view being a mirror image thereof;
FIG. 3 is a top plan view thereof;
FIG. 4 is a bottom plan view thereof;
FIG. 5 as a top perspective view of a second embodiment of my new design of FIGS. 1-4;
FIG. 6 is a right side elevational view, the left side elevational view being a mirror image thereof;
The broken line showing of a fork blade in FIGS. 1-8 are environmental only and form no part of the claimed design.
